UNITED STATES PATENT OFFICE

171,020

COMBINED BIRDBATH AND SOLARIUM FOR GROWING PLANTS

Alvin S. Anderson, Chicago, Ill.

Application October 13, 1952, Serial No. 21,821

Term of patent 14 years

(Cl. D91—4)

To all whom it may concern:

Be it known that I, Alvin S. Anderson, a citizen of the United States, residing at 551 North Austin Blvd., Chicago, Illinois, have invented a new, original, and ornamental Design for a Combined Bird Bath and Solarium for Growing Plants, of which the following is a specification, reference being had to the accompanying drawing, forming part hereof.

The figure is a perspective view of a combined bird bath and solarium for growing plants showing my new design.

I claim:

The ornamental design for a combined bird bath and solarium for growing plants, as shown.

ALVIN S. ANDERSON.
